VENTILATED TOILET

Andrew P. Riedele, Los Angeles, Calif.

Application August 21, 1945, Serial No. 611,719

6 Claims. (Cl. 4—217)

1

This invention relates to ventilated toilets of the general character embodied in my Letters Patent No. 2,389,165, issued November 20, 1945.

The invention of the above identified application provides a ventilating adapter on which the toilet seat is mounted for rising and lowering movements with respect to the toilet bowl, with the adapter being secured to the bowl and having an inlet opening between the seat and bowl at the rear of the latter, through which odors from the bowl pass into the adapter and from the latter into a suitable stack in the wall of the room, so as to obviate contamination of the air in the room.

An object of the present invention is to provide a ventilated toilet of the above described general character embodying a ventilating adapter which functions in its installed position on the toilet bowl at the rear of the seat, to pivotally mount the latter for its rising and lowering movements and to conduct bowl odors into a wall stack, the adapter being structurally characterized by means enabling adjustment of the seat relative to the toilet bowl to be effected longitudinally, transversely and vertically of the bowl so as to accurately fit the seat and adapter to the bowl for sealing engagement of the seat with the bowl, irrespective of (1) inequalities in the bowl rim, (2) variations in the spacing of the usual openings provided through the back of the bowl for the pair of stud bolts which are normally utilized to mount the seat on the bowl, and (3) variations in the spacing between the pivotal mounting brackets on the seat, all to the end of compensating for manufacturing inaccuracies in dimensions of toilets, and rendering the invention capable of practically universal installation on the products of different toilet manufacturers.

Another object of this invention is to provide a ventilated toilet whose ventilating adapter is of simple and durable construction which lends itself to quantity production at a low cost, and which does not require any structural modification whatsoever of standard toilets, to fit the invention thereto, thus inexpensively placing the invention within the reach of the greatest number of users.

With these and other objects in view, the invention resides in the combinations, arrangements and functional relationships of elements as set forth in the following specification and particularly pointed out in the appended claims.

In the accompanying drawing,

Figure 1 is a plan view of one form of ventilated toilet embodying the present invention;

2

Figure 2 is an enlarged vertical longitudinal sectional view taken on the line 2—2 of Figure 1;

Figure 3 is a bottom plan view taken on the line 3—3 of Figure 2;

5 Figure 4 is an enlarged fragmentary sectional view taken on the line 4—4 of Figure 1;

Figures 5, 6 and 7 are fragmentary horizontal sectional views taken, respectively, on the lines 5—5, 6—6 and 7—7 of Figure 4; and

10 Figure 8 is a transverse vertical sectional view taken on the line 8—8 of Figure 4.

Referring specifically to the drawing, the invention is shown for the purpose of illustration, associated with a conventional form of toilet fixture composed of the usual bowl B and seat S with or without a cover C. The seat and cover are respectively provided with the usual pairs of hinge brackets 10 and 11 respectively, by which they are pivotally mounted on a hinge pin 12 usually supported by stud bolts 14 having nuts 15 passing through openings 16 in a rearward extension or shelf 17 of the bowl B, which is flush with the top surface 18 of the bowl rim as shown in Figure 2. However, in the use of the present invention, the stud bolts 14 are screwed permanently into threaded bores 19 of brackets 20 which are rectangular metal blocks (Figures 4, 5 and 8) and form part of a ventilating adapter designated generally at V.

15 The ventilating adapter V includes an open ended tubular body 21 of sheet metal which is cylindrical in cross section and is provided with a peripheral, longitudinally extending slot 22. The slot 22 is bounded by a rectangular and hollow base flange 23 projecting laterally from the body 21 and having an open bottom and an open forward end to co-act with the shelf 17 of the bowl B in forming an inlet duct 24 to the body 21 from the space between the seat S and the bowl rim 18 at the rear end of the seat when lowered on the bowl in the installed position of the adapter as shown in the drawings.

20 Adjacent the threaded vertical bores 19, the brackets 20 are provided with smooth vertical bores 26 slidably receiving posts 27 for vertical adjustment relative to the bowl, and adapted to be clamped in a selected adjusted position by set screws 28 threaded into the brackets 20 and rendered accessible to a screw driver through openings 29 in the base flange 23 of the adapter as typically shown in Figure 5.

25 The upper ends of the bores 26 of the brackets 20 are bounded by externally threaded collars 30 projecting freely through transversely extending slots 31 in the top of the base flange 23 (Figure 7) and having nuts 32, adapted, when tightened,

to clamp the ventilating adapter V rigidly in adjusted position to the bowl B through the medium of the brackets 20, which latter will be concealed within the base flange 23.

At their upper ends, the posts 27 are provided with horizontal sleeves 33 in which are slidably mounted for adjustment forwardly and rearwardly of the bowl, cylindrical arms 34 having sleeves 35 receiving the hinge pin 12 between the hinge brackets 10 and 11 as shown in Figure 1. Set screws 36 (Figure 6) threaded into the sleeves 35, rigidly support the hinge pin 12 in a selected position of adjustment.

Sealing members 37 in the form of curved strips of elastic rubber, are secured to the underside of the seat S by suitable fastening members 38, and are spaced apart at the front of the seat to provide an air inlet 39 to the interior of the bowl between the seat and bowl rim when the sealing members rest upon the latter in the lowered position of the seat as shown in Figure 2.

The rear ends of the sealing members 37 terminate short of the hinge brackets 10, and flanged covers 40 are secured to the seat by fastening members 41 to form continuations of the sealing members to the forward end of the air inlet duct 24 of the ventilating adapter. When installing the invention, one end of the body 21 is closed by a cup shaped cap 42, whereas the other end of the body is connected by suitable pipe fittings 43 to a stack (not shown) in the wall of the room leading to the attic space or the atmosphere.

The operation of the invention is as follows:

With the invention applied to a toilet as shown, and the toilet in use, bowl odors will be conducted by natural thermal currents from the bowl B through the inlet duct 24 into the body 21 and thence into the stack, this action causing room air to be drawn through the inlet 39 and across the interior of the bowl from the front to the rear thereof so as to produce a continuous withdrawal of odors from the bowl, thus insuring that such odors will not contaminate the room air.

It will be clear that by the provision of the brackets 20, the center to center spacing of the posts 27 can be varied to compensate for inaccuracies in the spacing of the openings 16 of the bowl shelf 17, for by loosening the nuts 15, the brackets 20 can be adjusted about the axes of the respective stud bolts 14. Furthermore, vertical adjustment of the seat S to bring its sealing members 37 into sealing engagement with the top surface of the bowl rim 18 can be accomplished irrespective of the unevenness of such surface, by the provision of the posts 27 vertically adjustable in the respective brackets 20. Also, forward and rearward adjustment of the seat S to bring it into a symmetrical and centered relationship to the bowl, can be effected by the provision of the arms 34 adjustable horizontally and longitudinally of the bowl in the sleeves 33 of the posts 27.

Thus it will be manifest that irrespective of any inaccuracies in the dimensions of the products of different manufacturers, as very commonly occur due to practical difficulties in the molding of toilet bowls with any degree of precision, the invention can be readily installed on the toilet without any structural modification of the latter. By the above described arrangement and functional relationships of elements, the range of use of the invention is extended to any

and all toilets of the type set forth regardless of the source of manufacture.

I claim:

1. In a ventilated toilet, a bowl; a seat therefor; a ventilating adapter comprising a tubular body adapted for connection to a vent pipe and having a hollow base portion resting on the bowl at the rear thereof and adapted to form an inlet duct to conduct odors into said body; a pair of brackets in said base portion at opposite sides of said inlet duct and having studs securing said bracket to the bowl; said brackets having posts provided with horizontal sleeves and being mounted on said brackets at locations eccentrically related to the axes of said studs, for vertical adjustment; arms having sleeves and being mounted in said sleeves of the posts for horizontal adjustment forwardly and rearwardly of the bowl; and means pivotally mounting the seat from the sleeves of said arms for rising and lowering movements.

2. In a ventilated toilet, a bowl; a seat therefor; a ventilating adapter comprising a tubular body having an outlet adapted for connection to a vent pipe and provided with a hollow base portion resting on the bowl at the rear thereof and adapted to form an inlet duct to conduct bowl odors into said body; a pair of brackets in said base portion at opposite sides of said inlet duct and having depending bolts passing through openings in the bowl; nuts on said bolts for securing the brackets to the bowl in a selected position of pivotal adjustment about the axes of the bolts; said brackets having vertical bores offset with respect to said bolts; threaded collars on the brackets bounding said bores and projecting through openings in said base portion; nuts on said collars for securing the said body to said brackets; posts having horizontal sleeves and being mounted in said bores for vertical adjustment; means for securing the posts in a selected position of adjustment; arms having sleeves and being mounted in said sleeves of the posts for horizontal adjustment forwardly and rearwardly of the bowl; means for securing said arms in selected positions of adjustment; a hinge pin mounted in the sleeves of said arms; and means mounting the seat on the hinge pin for rising and lowering movements.

3. A ventilating device for toilets comprising: a pair of brackets; means adapted to secure the brackets in spaced relation on the toilet bowl for pivotal adjustment towards and away from each other about vertical axes; a tubular body having an outlet and a hollow base portion projecting laterally therefrom and defining an inlet for bowl odors into the body; means for securing said base portion to the brackets in covering relation to the latter; means coacting with said brackets to pivotally mount the toilet seat from the brackets for rising and lowering movements with respect to the toilet bowl; means mounting said pivotal mounting means for adjustment relative to the brackets in directions forwardly and rearwardly of the bowl so as to correspondingly shift the position of the toilet seat; and means coacting with the brackets and the last said means to mount the toilet seat for adjustment vertically.

4. A ventilating device for toilets comprising: a pair of brackets; means adapted to secure the brackets in spaced relation on the toilet bowl for pivotal adjustment towards and away from each other about vertical axes; a tubular body having an outlet and a hollow base portion project-

ing laterally therefrom and defining an inlet for bowl odors into the body; said brackets having vertical bores and threaded collars bounding same; said base portion having openings through which said collars project; nuts on said collars securing the base portion to the brackets; means vertically adjustable in said bores; means mounted on said vertically adjustable means for adjustment horizontally in directions forwardly and rearwardly of the toilet bowl; and means adapted to pivotally mount the toilet seat on the last means for rising and lowering movements with respect to the toilet bowl.

5. A ventilating device for toilets comprising: a pair of brackets; means adapted to secure the brackets in spaced relation on the toilet bowl for pivotal adjustment towards and away from each other about vertical axes; a tubular body having an outlet and a hollow base portion projecting laterally therefrom and defining an inlet for bowl odors into the body; said brackets having vertical bores and threaded collars bounding same; said base portion having openings through which said collars project; nuts on said collars securing the base portion to the brackets; posts having sleeves and being vertically adjustable in said bores; means for securing the posts in selected positions of adjustment; arms having sleeves adapted to pivotally mount the toilet seat for rising and lowering movements with respect to the toilet bowl and being mounted in said sleeves of said posts for adjustment horizontally in directions as will adjust the seat forwardly and rearwardly of the toilet bowl; and means for securing said arms in selected positions of adjustment.

6. A ventilating device for toilets comprising: a pair of brackets; means adapted to secure the

brackets in spaced relation on the toilet bowl; a hollow body having an outlet to a vent pipe and an inlet-forming base portion adapted to rest on the toilet bowl; means for securing said base portion to the brackets; means mounted in said brackets for vertical adjustment with respect to the toilet bowl; means for securing said vertically adjustable means in selected positions of adjustment; means mounted on said vertically adjustable means for horizontal adjustment in directions forwardly and rearwardly with respect to the toilet bowl and adapted to mount the toilet seat for rising and lowering movements with respect to the bowl; and means for securing the last means in selected positions of adjustment.
